UNITED STATES PATENT OFFICE.

MAX HEYMANN, OF CHICAGO, ILLINOIS.

DISPLAY APPARATUS.

1,181,664.

Specification of Letters Patent. Patented May 2, 1916.

Application filed January 25, 1915. Serial No. 4,114.

To all whom it may concern:

Be it known that I, MAX HEYMANN, subject of the Emperor of Germany, residing at Chicago, in the county of Cook and State 5 of Illinois, have invented a certain new and useful Improvement in Display Apparatus, of which the following is a full, clear, concise, and exact description, reference being had to the accompanying drawings, forming 10 a part of this specification.

My invention relates to that class of advertising devices employing display belts that are arranged in zigzag formation.

The invention has for its object a novel 15 construction whereby the spacing required for the belt structure is reduced.

I will explain my invention more fully by reference to the accompanying drawings showing the preferred embodiment thereof 20 and in which—

Figure 1 is a front view; Fig. 2 is a perspective view of the lighting equipment; Fig. 3 is a side view of the structure as it appears in Fig. 1, the case for the motor 25 being shown in section; Fig. 4 is a plan view of the machine with the top of its casing removed; Fig. 5 is a sectional view on line 5 5 of Fig. 4; Fig. 6 is a view in plan, partially in section, of the structure at the left 30 hand end of the device; Fig. 7 is a sectional plan view of the structure; Fig. 8 is an end sectional elevation; Fig. 9 is a view on line 9 9 of Fig. 10; Fig. 10 is a view on line 10 10 of Fig. 9; and Figs. 11 and 12, are 35 details respectively taken on lines 11 11 and 12 12 of Fig. 10.

Like parts are indicated by similar characters of reference throughout the different figures.

40 The display belt 1 is provided with display areas 2 which are desirably in the form of unfilled perforations, these perforations being assembled to formulate the elements of the display matter such as words, figures 45 and symbols. The belt is caused to travel, preferably continuously, from right to left and is looped in a manner to present a limited area thereof to view. The forward stretch of the belt, as illustrated clearly in 50 Figs. 1 and 7, is the portion thereof that is presented to view, this portion being ever changing owing to the preferably continuous movement which is imparted to the belt. A housing is provided for the equipment 55 which is in the form of a rectangular casing A desirably having its front wall

in the form of a pane of transparent glass 3, whereby there is constituted a display opening in the casing A through which the traveling belt may be viewed and the ever changing sign carried thereby may be seen. A source of light is provided behind the traveling belt, this light source being desirably formed of a plurality of lighting centers in the form of incandescent lamps 4 receiv- 60 able within lamp sockets 5 that are mounted in the top side of a channel 6 which is secured to the bottom of the housing 7 by bolts 8, the space confined by the channel and the bottom of the housing receiving the bot- 70 tom portions of the sockets and the circuit conductors 9 that extend thereto. The housing 7 is narrower at the back than at the front, the end walls converging toward each other rearwardly. The inner surfaces of 75 the top, bottom, back, and end walls of the housing act as reflectors to throw light forwardly so that it may more fully emanate through the perforations 2 there to cause 80 lighted areas which contrast with the surrounding area afforded by the belt, the belt being desirably formed of opaque material such as suitable paper. In order that the lighted areas at the perforations 2 may be substantially homogeneous in appearance 85 and in order that the lamps may not be individually seen by the observer I interpose a light diffusing or equalizing element between the observer and the lamps. This light diffusing element desirably does not 90 travel with the belt but is preferably made stationary and in the form of a pane of translucent glass. The translucent light transmitting medium 10 is desirably interposed between the front stretch of the 95 traveling belt and the lamp house. Any suitable means may be employed for effecting the travel of the belt and as the rate of travel is desirably uniform I desirably employ an electric motor 11 which is geared down to drive at sufficiently slow speed to afford time within which the characters that are presented to view may be discerned and in which the language that they spell may be read if the characters happen to be in the 105 form of word forming letters. Motion is transmitted from the motor 11 by means of the belt 12 to the worm 13, thence to the worm gear 14, and the intermediate pinion 15. The pinion 15 drives rollers 16 through 110 the intermediation of the pinions 17 and idler pinions 18. The rollers 16 thus con-

stitute initially driven rollers, being located at the right hand end of the casing A and there turning in such direction as to cause the front and display stretch of the belt 1 to 5 travel to the left between the glass panes 3 and 10.

Any particular perforation or display area 2 upon the display belt may be traced in its travel from the foremost driving roller 10 16, thence between the panes of glass 3 and 10 over the foremost idler roller 19, the rearmost idler 20, the guide 21, which is preferably stationary, the guide 22 which is also preferably stationary, the rearmost driving 15 roller 16, the guide 22 immediately in front of the aforesaid guide 22, the guide 21 immediately in front of the aforesaid guide 21, the idler roller 23, thence over the next guides 21 and 22 to the next roller 16 immediately 20 in front of the aforesaid roller 16, thence over the next guides 22 and 21 to the next idler roller 23 immediately in front of the last aforesaid idler roller 23, the display opening whose travel is being traced 25 zigzagging back and forth until it reaches its starting point at the foremost driving roller 16. Thus the display belt travels in a closed path which is mainly zigzag, which it is enabled to do by reason of the driving 30 bight forming rollers 16 and the driven bight forming rollers 19, 20 and 23, the foremost and rearmost rollers 16 and the rollers 19 and 20 defining a portion of the path of travel which substantially embraces the balance and zigzag portion of the path. All 35 the rollers excepting the rollers 23 desirably have stationary axes of rotation but the rollers 23 are mounted in a frame 24 which may turn upon a shaft 25. A spring 26 is 40 looped about the shaft 25, one end of the spring pressing against a stationary pin 27 while the other end of the spring presses against a pin 28 carried by the pulley frame 24. There is desirably such a spring structure 45 at the top and bottom of the frame. The springs tend to move the frame 24 in a counter-clockwise direction and do so move this frame when there is slack in the belt in order that the slack may be taken up. 50 When the belt contracts the spring will yield to permit of such contraction. In this manner the various stretches of the belt are maintained taut for the prime purpose of maintaining the front and display stretch 55 of the belt taut in order that the characters formed therein or borne thereby may not be warped in appearance. The tractive engagement between the driving rollers 16 and the belt is thus also maintained substantially 60 uniform so that the rate of belt travel may be substantially constant when desired. The guides 21 and 22 are desirably made of sheet

metal to afford narrow passages toward which the belt stretches behind the lamp house converge, whereby these belt stretches 65 are closely approximated and may move within the narrow space which intervenes between the lamp house and the back wall of the casing A.

The frame 24 desirably includes a scalloped guide wall 29 which is disposed to the left of the rollers 23 and which enables the belt to be properly guided when the apparatus is being assembled. A similar wall 30 is provided upon the right hand side of the 75 right hand frame 31 that carries the roller 16 and serves a similar purpose. Stationary walls 32 and 33 are provided to define a channel to guide the belt between the rollers 19 and 20 to aid in the assembly of the apparatus, the channel thus defined being desirably tangential to these two rollers.

While I have herein shown and particularly described the preferred embodiment of my invention I do not wish to be limited to 85 the precise details of construction shown as changes may readily be made without departing from the spirit of my invention, but

Having thus described my invention I claim as new and desire to secure by Letters 90 Patent the following:—

Display apparatus including a display belt; means for effecting and guiding the travel of the belt to afford a forward display stretch and inclusive of two bight forming 95 elements at each end of the apparatus and at the front thereof around which the belt passes; an additional bight forming element within the space around which the belt is guided; a plurality of additional bight 100 forming elements at each end of the apparatus around which the belt is passed in a zigzag path; a source of light located to the rear of the display stretch of the belt; a reflector before which the source of light is 105 disposed and serving to reflect the light forwardly; a body of translucent material interposed between the display belt and the source of light; and a guide structure located to the rear of the reflector and having 110 narrow and closely approximated guiding passages in which stretches of the belt other than the display stretch are received and which guide structure closely approximates the said stretches of the belt to reduce the 115 space to the rear of the reflector required for the belt stretches there passing.

In witness whereof, I hereunto subscribe my name this twenty-second day of January, A. D., 1915.

MAX HEYMANN.
